UNITED STATES PATENT OFFICE.

BRUNSON S. McCUTCHEON, OF PLAINFIELD, NEW JERSEY.

WRINGER.

Application filed September 20, 1920. Serial No. 411,548.

To all whom it may concern:

Be it known that I, BRUNSON S. McCUTCHEON, a citizen of the United States of America, residing at Plainfield, in the county of Union and State of New Jersey, have invented certain new and useful Improvements in Wringers, of which the following is a specification.

This invention relates to clothes wringers and consists in certain improvements in the construction thereof to be hereinafter fully described and particularly pointed out in the claims.

The invention has for its object to provide means for instantly releasing the pressure on the rolls, when the operator gets her hand caught by the rolls or for the purpose of releasing abnormally large or bunched articles which may be drawn, between the rolls.

Other and further objects will be part apparent and in part described as the specification is proceeded with.

In the accompanying drawings:

Figure 1 is a plan view of my invention; Figure 2 is a vertical longitudinal sectional view of the same;

Figure 3 is a horizontal sectional view of the bushing;

Figure 4 is a side elevation of same;

Figure 5 is a plan view of sleeve showing a portion of the angle plate;

Figure 6 is a vertical sectional view of the same; and

Figure 7 is a diagrammatic view of sleeve and bushing showing manner in which they cooperate.

Referring more particularly to the drawings in which like reference numerals refer to corresponding parts throughout the several views 5 denotes a wringer frame comprising end bars or uprights 6 and side bars 7. Pressure rolls 8, only the upper one of which is shown in the drawing, are suitably mounted in the end bars 6 and are maintained under suitable compression by means of spiral compression springs 10 seated at their lower ends against the bearing blocks 11 of the roll 8, it being understood that these bearing blocks are slidably mounted in the end bar 6. Seated in the tops of the compression springs 10 are a pair of cup shaped members 9 in turn engaged by compression screws 12 the mounting and operation of which will be presently described.

Bolted to and extending over the tops of

the end bars 6 of the wringer frame are a pair of angle plates 13 having upstanding sleeves 14 formed integral therewith. The interior of the sleeves 14 are provided with vertical ribs or projections 15 having inclined faces 16 adapted to engage or mesh with the inclined faces 17 of vertical ribs or projections 18 formed on bushings 19 in turn rotatably mounted in the sleeves 14. These ribs 15 and 18 in effect form spiral threads. The bores 20 of the bushings 19 are threaded for the reception of the compression screws 12. Consequently when the screws 12 are screwed down by means of the crank handles 21 formed thereon, the movable upper compression roll may be placed under any desired compression, through the action of the compression springs 10.

Owing to the fact that the normal upward thrust of the compression roll 8 tends to rotate the bushings 19 in the sleeves 14 in an anticlockwise direction thus causing the bushings and with them the compression screws to move upwardly thereby reducing the compression of the rolls, some means must be provided for locking the bushings against such rotation until manually released. This is accomplished by means of a rod or the like 22 adapted to extend diagonally across the top of the wringer frame with its ends seated in diagonally disposed pockets 23 formed in the angle plates 13. The ends of this rod when so seated lie directly in the path of rotation of the arms 24 formed on the bushings and of course serve to hold the bushings stationary.

In the event of the operator having her hand drawn between the rolls, all that is necessary for her to do to relieve the compression between and permit separation of the rolls is to strike or bear against the rod 22 causing the latter to be pushed out of the open ends 25 of the pockets 23, thus freeing the rod from engagement with the arms 24. The rod can be readily pushed out of the pockets from either side of the wringer frame and the release of one end of the rod automatically results in the release of the other end, in an obvious manner. The moment the rod 22 is moved to an inoperative position the upward thrust of the roll 8 will cause the bushings to rotate on the principle of a spiral, but much faster, owing to the shape and construction of the co-operating ribs 15 and 18 on the sleeves and

bushings respectively causing the bushings to move upwardly in a rotary manner to the dotted line position Figure 7 or until this movement is arrested by the shoulders 26 on the ribs 18 engaging beneath the ends of the ribs 15. It will thus be seen that there is no likelihood of the bushings working out of their respective sleeves. It will also be noted that the ribs 15 are so spaced as to 10 permit assembly of the bushings within the sleeves when the ribs 18 are aligned with the spaces between the ribs 15.

Any suitable means such as chains 27 may be employed to prevent the rod 22 from falling off or down into the interior of the frame.

Having thus described my invention, what I claim is:

1. A clothes wringer comprising a frame, 20 rolls and compression means therefor mounted in said frame, angle plates secured to said frame at each end thereof, said plates being formed with sleeves having interior ribs thereon, bushings rotatably and slidably 25 mounted in said sleeves and having exterior ribs, the ribs on said sleeves and said bushings having engaging oppositely inclined portions, compression screws mounted in said bushings engaging said compression 30 means whereby the upward thrust of said rolls causes said bushings to rotate upwardly in said sleeves, and means for normally preventing such upward movement of said bushing.

35 2. A clothes wringer comprising a frame, rolls and compression means therefor mounted in said frame, a bushing rotatably and slidably mounted in said frame, a compression screw carried by said bushing engaging 40 said compression means permitting the raising of said bushing when rotated but preventing such raising except when rotated, said bushing adapted to be raised in said frame by the upward thrust of the compression means to relieve said compression, and readily releasable means for preventing 45 such rotation of the bushing.

3. A clothes wringer comprising a frame, rolls and compression means therefor mount-

ed in said frame, sleeves mounted on each 50 end of the frame, bushings in said sleeves having arms thereon, said bushings and sleeves having ribs with inclined engaging portions, and compression screws carried by 55 said bushings and engaging said compression means whereby said bushings are adapted to be rotatably raised in said sleeves by the upward thrust of said compression means to relieve the compression between the rolls, and quick releasable means extending 60 between the arms on said bushings for normally preventing such rotation of said bushings.

4. A clothes wringer comprising a frame, 65 rolls and compression means therefor mounted in said frame, sleeves mounted on opposite ends of the frame, bushings rotatably mounted in said sleeves, said sleeves and bushings having longitudinal spaced intermeshing ribs formed with engaging inclined faces, compression screws carried by 70 said bushings engaging said compression means, whereby the upward thrust of said compression means causes the bushings to rotate and the ribs of said bushings to ride 75 upwardly between the ribs of said sleeves to relieve the compression between said rolls, means on the ribs of said bushings adapted to limit said upward movement and means for normally preventing the rotation of 80 said bushings.

5. A clothes wringer comprising a frame, rolls and compression means therefor mounted in said frame, sleeves mounted on opposite ends of the frame, bushings rotatably mounted in said sleeves, said sleeves and bushings having spaced intermeshing ribs formed with inclined engaging faces, compression screws carried by 85 said bushings engaging said compression means, whereby the upward thrust of said compression means causes the bushings to rotate and the ribs of said bushings to ride upwardly 90 between the ribs of said sleeves, and quick releasable means for locking said bushings 95 against rotation.

In testimony whereof I affix my signature.
BRUNSON S. McCUTCHEON.
